UNITED STATES PATENT OFFICE.

HARRY BRADLEY ROWAN, OF NORTH ATTLEBORO, MASSACHUSETTS, ASSIGNOR TO WHITING & DAVIS COMPANY, A CORPORATION OF MASSACHUSETTS.

HAND BAG.

Application filed October 1, 1924. Serial No. 740,915.

To all whom it may concern:

Be it known that I, HARRY BRADLEY ROWAN, a citizen of the United States, residing at North Attleboro, in the county of Bristol, State of Massachusetts, have invented certain new and useful Improvements in Hand Bags; and I do hereby declare the following to be a full, clear, and exact description of the invention, such as will enable others skilled in the art to which it appertains to make and use the same.

This invention is directed to the provision of a novel form of hand bag, preferably one in which the flexible material constituting the receptacle, and in this instance the receptacles, is of flexible metallic link mesh; more particularly the invention relates to a novel form of hand bag of that type which includes a casing for cosmetics mounted within the bag in such a way as to make it conveniently accessible.

The invention involves features of the construction of a bag of this character whereby a very attractive appearance is produced in a bag which can be carried conveniently and readily manipulated.

One of the distinguishing characteristics of the new construction is in the duplex arrangement of the bag receptacles. Two circular metallic members are pivoted together at one side and on the opposite side are provided with a clasp whereby they may be held together with their edges in contact and the flexible material of each of the two bag receptacles is secured to one of these circular members.

With such a construction, when the two circular members are held by the clasp with their edges in contact, the bag is closed; and the members may be opened by unclasping them and turning them relatively about their pivotal connection to give access to the two bag receptacles which hang down parallel to each other from the two circular members.

Another of the distinguishing characteristics of the invention is in the provision of a casing for cosmetics which lies within the bag and is made accessible for use by opening it. This casing is pivotally mounted so that it may turn relatively to either one of the two circular members. It is preferably pivotally mounted on the same axis as that about which the two circular

members turn relatively. This casing has two receptacles in it located on opposite sides. Either one may be made accessible by turning the circular member and receptacle which cover that one relatively to the casing, or both receptacles may be made accessible at once by turning both of the circular members relatively to the casing. Preferably the casing has a circumferential flange which may be received snugly in either of two grooves provided in the adjacent faces of the circular members so that when access is required to only one of the receptacles in the casing, the flange of the casing lies in the groove of the circular member on the opposite side with the surface of the flange flush with the surface of the member. For convenience in manipulating the casing as desired with relation to the two circular members, it may be provided with a radial projection which may be engaged by the finger of the user and in order that this projection may be of adequate size and at the same time permit the two circular members to close tightly, grooves are preferably provided in the adjacent faces of the circular members corresponding to the location and size of the projection.

The bag thus constructed is carried by a chain which has its ends secured to the two circular members.

The preferred embodiment of the invention is illustrated in the accompanying drawings in which Fig. 1 is an end elevation of the bag; Fig. 2 is a central section on an enlarged scale; Fig. 3 is a top view of the bag when opened wide with the casing to one side, the flexible bag material being omitted; and Fig. 4 is a view corresponding to Fig. 1 with the bag wide open and the casing in an intermediate position.

Referring to these drawings, the two circular members which constitute the frame members of the bag are shown at 5 and 6. At their lower edge they are pivoted together by a pivot shown at 7. At the upper edge of the circular members is a clasp for holding them detachably in the closed position. This clasp is shown at 8 mounted on the circular member 6 with its end adapted to pass through and spring over the edge of an opening in a projection 9 on the member 5. This projection and a similar one on the member 6 have the ends of a

chain 10 for suspending the bag secured to them.

The two bag receptacles 11 of flexible material, preferably metallic link mesh, are secured to the circular members 5 and 6, the material at the edge of the opening in each receptacle being secured in any suitable manner to the edge of the circular member around the entire circumference thereof.

Fig. 1 shows the bag in its closed position. By releasing the clasp 8, the two circular members 5 and 6 may be turned relatively about pivot 7 to the open position indicated in Fig. 4, thus giving access to the two receptacles which hang down parallel to each other as is indicated in Fig. 4. When the bag is closed the two receptacles hang down parallel to each other as shown in Fig. 1 and unless they are more or less filled, they lie close together and present a very attractive appearance.

With the bag thus formed is combined a casing for cosmetics. This casing is in the form of a disc having receptacles on opposite sides thereof and it is pivotally mounted within the bag so that it may be turned about its pivot to give ready access to either of the two receptacles. Preferably it is pivotally mounted upon the pivot pin 7 by which the two circular members 5 and 6 are connected. The casing consists of two metallic rings 12 and 13, the latter having a circumferential flange over which the metal of the former is turned in such a way as to form on the casing an outwardly extending circumferential flange shown at 14. On the ring 12 is secured a circular metallic piece 15 which with a pivotally mounted cover 16, constitutes a receptacle which may receive a compact 17, a puff 18 and a mirror 19. The member 15 also forms the bottom of a receptacle on the opposite side of the casing which may receive a compact 20, a puff 21 and a mirror 22. This receptacle is closed by a cover 23 pivotally mounted upon the ring 13.

The rings 5 and 6 have the metal at their adjacent edges shaped as shown at 24 and 25 to form circumferential grooves in which the flange 14 on the casing is received. On the casing is a radial projection 26 forming a finger piece by which the casing may be turned relatively to either of the circular members 5 and 6. In order that this projection may be of adequate size and still not prevent the circular members 5 and 6 from coming together face to face as shown in Fig. 2, grooves are formed in the metal of the rings 5 and 6 as shown at 27 in Figs. 3 and 4 of a size and in the position for receiving projection 26.

The covers 16 and 23 for the two receptacles of the casing are provided with projections 28 for use in moving them to the open position, and if necessary the flange

24 on the circular member 5 may be cut away sufficient to permit the free passage of the projection 28 on the cover 23.

The drawings illustrate the construction which I prefer to employ both with respect to utility and attractive appearance, but it is to be understood that the features of the invention may be employed in constructions differing considerably from that shown in the drawings. For instance, the members 5 and 6 are shown as circular, and the parts of the casing are circular to correspond thereto, but these may be more or less oval or of some polygonal shape and all such generally circular shapes I mean to include by the expression circular member which I have used in referring to the parts 5 and 6.

I claim:

1. A hand-bag comprising the combination of two circular members pivoted together at one side, a clasp for holding the two members detachably together at a point opposite the pivot, two bag-members of flexible material each secured to one of the circular members, a case pivotally mounted within the bag to turn relatively to both of the circular members, and a circumferential flange on the case adapted to be received in grooves provided therefor in the adjacent faces of the said circular members. 95

2. A hand-bag comprising the combination of frame members pivoted together on one side and having inwardly extending flanges shaped to form circumferential grooves, means opposite the pivot for holding the two members detachably together, bag members secured to the frame members, and a case pivotally mounted within the bag to turn relatively to both of the frame members, said case having a circumferential flange adapted to fit into the circumferential grooves of said frame members. 100

3. A hand-bag comprising the combination of frame members pivoted together on one side and having inwardly extending flanges shaped to form circumferential grooves, means opposite the pivot for holding the two members detachably together, bag members secured to the frame members, a case pivotally mounted within the bag to turn relatively to both of the frame members, said case having a circumferential flange adapted to fit into the circumferential grooves of said frame members, a projection on said case and depressed portions in said frame members adapted to align and form an opening to receive said projection. 115

4. In a hand-bag, a frame comprising two members pivoted together at one side, means opposite said pivot for holding said members detachably together, said members having inwardly extending flanges adapted to abut against each other in closed position and said flanges shaped to form circumferential grooves, and a case pivotally mounted with- 120

in said frame members and having a circumferential flange adapted to fit into the circumferential grooves of said frame members.

5. In a hand-bag, a frame comprising two members pivoted together at one side, means opposite said pivot for holding said members detachably together, said members having inwardly extending flanges adapted to

10 abut against each other in closed position

and said flanges shaped to form circumferential grooves, a case pivotally mounted within said frame members and having a circumferential flange adapted to fit into the circumferential grooves of said frame members, said case having receptacles formed on opposite sides thereof, and closure for said receptacles pivoted to said case. 15

In testimony whereof I affix my signature.

HARRY BRADLEY ROWAN.
